(57) **CLAIM**

The ornamental design for a foregrip for firearm, as shown and described.

DESCRIPTION

FIG. 1 is a front perspective view of a foregrip for a firearm showing my new design.

FIG. 2 is a front view of the foregrip.

FIG. 3 is a rear view of the foregrip.

FIG. 4 is a right view of the foregrip.

FIG. 5 is a left view of the foregrip.

FIG. 6 is a top view of the foregrip.

FIG. 7 is a bottom view of the foregrip.

FIG. 8 is a rear perspective view of the foregrip.

FIG. 9 is a perspective view of the foregrip, illustrating the foregrip downwardly extended from the firearm at a perpendicular direction.

FIG. 10 is a perspective view of the foregrip, illustrating the foregrip being pivotally folded to the left side of the firearm; and,

FIG. 11 is a perspective view of the foregrip, illustrating the foregrip being pivotally folded to the right side of the firearm. The broken line portion of the figure drawings is included to show unclaimed subject matter only and forms no part of the claimed design.
